UNITED STATES PATENT OFFICE.

CHRISTOPHER STRAUB, OF LONG ISLAND CITY, NEW YORK.

DRILL.

SPECIFICATION forming part of Letters Patent No. 739,946, dated September 29, 1903.

Application filed October 25, 1902. Serial No. 128,789. (No model.)

To all whom it may concern:

Be it known that I, CHRISTOPHER STRAUB, a citizen of the United States, residing at Long Island City, in the county of Queen's and State 5 of New York, have invented new and useful Improvements in Drills, of which the following is a specification.

The drill shown belongs to the class generally known as "ratchet-drills," although a 10 clutch or other mechanism not strictly ratchet has been shown in this art, and, moreover, the invention is not affected by this detail.

By means of this invention a brace can be obtained for the tool other than the customary 15 center or hard-steel point. Say, for example, a floor of a room is to be bored or drilled, then by a tube or the like—say a piece of piping of sufficient length and diameter—a brace for the tool can be obtained at the ceiling 20 of the room or other comparatively distant point. Such bracing at a distant point can be obtained without the easy working or the steadiness of the tool being interfered with, so that steady work can be done and 25 quivering avoided.

This invention is illustrated in the annexed drawings, in which—

Figure 1 is a sectional elevation of a drill embodying this invention. Fig. 2 shows a 30 brace.

Certain parts of the drill are well known—as, for example, the sleeve *g*, with center or steel point *i*, and also the ratchet-wheel or equivalent part *d*, adapted for engagement 35 by the lever and pawl. A suitable socket or engaging portion is provided for the bit or boring part *a*. A screw is shown at *h*, which does not screw directly into the sleeve, but into a tapped part or stem portion of shoulder-piece *k*. This latter piece *k* is screwed 40 into sleeve *g*. A jam-nut *l* is adapted to lock the parts *h* *k*, so as to prevent one screwing or rotating with regard to the other when not required. A loose or non-rotating flange or 45 washer *f* is adapted for the engagement of an extension or brace piece. This flange *f* is

shown below the top of the sleeve *g*, and a tubular extension or pipe *e* slipped over or about the sleeve against the flange and suitably braced or seated against a fixed body at 50 its other end will give a brace for the tool such as ordinarily obtained by aid of the center.

Ball-bearings for the flange will allow easy rotation of the latter, or rather of the drill, 55 when braced by aid of the flange. The balls can race or be supported on the shoulder-piece. A practical form of construction is to have the flange-washer somewhat cup-shaped or overhanging to keep the balls confined on 60 the shoulder-piece.

What I claim as new, and desire to secure by Letters Patent, is—

1. A drill comprising a sleeve, a loosely-mounted supporting-flange arranged below 65 said sleeve, and a tubular bracing extension detachably mounted upon said flange, supported thereby and surrounding said sleeve.

2. A drill comprising a sleeve, a shoulder-piece screwed into said sleeve, a screw attached to a drill-holder and extending in the shoulder-piece, and a flange loosely mounted on the shoulder-piece. 70

3. A drill comprising a sleeve, a shoulder-piece screwed into the sleeve, a screw in the 75 shoulder-piece, a flange loosely mounted on the shoulder-piece, and a tubular bracing extension surrounding said sleeve, detachably mounted upon and supported by said flange.

4. A drill comprising a sleeve, a brace-supporting flange loosely mounted below said sleeve, a tubular bracing extension surrounding said sleeve and detachably mounted upon and supported by said flange and suitable 80 ball-bearings for the said flange. 85

In testimony whereof I have hereunto set my hand in the presence of two subscribing witnesses.

CHRISTOPHER STRAUB.
